SLUG CASTING MACHINE

John H. Hilpman, Hollis, N. Y., assignor to Mergenthaler Linotype Company, a corporation of New York

Application July 30, 1935, Serial No. 33,815

20 Claims. (Cl. 199—50)

This invention relates to line casting machines of the general organization represented in U. S. Letters Patent to O. Mergenthaler No. 436,532, wherein circulating matrices are selected and assembled in line together with expanding space-bands, and the line thereafter presented to the front of a slotted mold, expanded or justified between a pair of confining jaws, and finally, after the casting operation, elevated from the 10 jaws and distributed.

In practice, it is necessary frequently to change the length of the slugs or "linotypes" produced, according to the width or measure of the page or column to be printed. Consequently, the mold 15 slot in which the slugs are cast is made variable in length, and one of the confining jaws is also made adjustable to correspond, so that lines of one length or another may be used at will.

The desirability of an adjustable line confining 20 jaw also arises when the machines are equipped for quadding or centering, since here too, the mold slot may be varied in length, demanding that the left hand jaw be adjusted accordingly; and, even in some cases when casting from molds 25 of normal length, it is desirable that the left hand jaw be adjustable as, for instance, in offset centering, i. e., when a line is centered with respect to an imaginary line offset from the true center line of the mold.

30 The present improvements provide for the adjustment of the left hand jaw to meet the various conditions stated, and such adjustments may be effected by the operator while seated at the keyboard, thus obviating the necessity of his leaving 35 the keyboard to effect the adjustment, as has previously been necessary in machines equipped for quadding and centering, with the result that greater facility and speed is obtained in the operation of the machine.

40 As usual, the jaws are arranged to be moved one toward the other to effect the quadding and centering movements, the right hand jaw for this purpose being connected directly to the actuating devices operable in quadding, whereas the left 45 hand jaw is connected to such devices through a banking block with respect to which the jaw is relatively adjustable. The left hand jaw is secured in its different adjusted positions by a toothed rod rotatably mounted so as to be moved 50 into and out of engagement with a complementary toothed section on the jaw, the arrangement being such that, when the toothed rod and section are in engagement, the adjusted position of the jaw is maintained, whereas when out of 55 engagement, the jaw may be moved with respect

to the toothed rod to its different adjusted positions.

The toothed rod is journalled at one end in the banking block previously referred to and, as the block is moved during a left hand quadding or 5 centering operation, said rod will move likewise. To accommodate this movement of the rod, it is arranged to telescope within a sleeve which extends through the right hand jaw, and which serves the additional purpose of rotating the rod 10 into and out of engagement with the left hand jaw.

The setting of the left hand jaw in its different line receiving positions is effected by an 15 adjusting rod secured directly to said jaw (not its banking block) and which telescopes into an adjusting sleeve likewise extending through the right hand jaw, the telescoping arrangement 20 accommodating the movement of the adjusting rod during a quadding or centering operation, as in the case of the toothed rod. The adjusting sleeve 25 is rotatable with respect to the adjusting rod and, in one angular position of adjustment, is coupled to the adjusting rod so that the left hand jaw may be moved to its different positions by adjusting the sleeve and consequently the rod longitudinally, it being understood that during such adjustment, the sleeve will extend beyond the vise frame at the right. In another angular position 30 of adjustment, the adjusting sleeve and the adjusting rod are slidable with respect to each other, not only to provide for the telescoping movement before alluded to, but in addition, to permit the sleeve to be returned to its normal position within the right hand jaw where it will be out of the 35 way during the operation of the machine.

It might be stated here that the right hand 40 jaw is slidable with respect to both sleeves in order that said jaw may be moved along the sleeves during a centering operation or when quadding with the right hand jaw.

The improvements further contemplate the 45 automatic disengagement of the toothed rod from its complementary toothed section in the left hand jaw as the adjusting sleeve is coupled to the adjusting rod (in which condition of the parts, the left hand jaw may be adjusted to its different line receiving positions) as well as the automatic engagement or re-engagement of the toothed rod with its complementary toothed section 50 as the adjusting sleeve is uncoupled from the adjusting rod. Provision is also made for maintaining the adjusting sleeve in its normal position out of the way during the operation of the machine.

- Referring to the drawings:
- Fig. 1 is a perspective view of the line clamping jaw equipped with the present improvements;
- Fig. 2 is a plan view of the parts shown in Fig. 1, the vise cap of the machine being broken away;
- Fig. 3 is a vertical longitudinal section on line 3—3 of Fig. 2;
- Fig. 4 is a vertical longitudinal section on line 4—4 of Fig. 2;
- Fig. 5 is a right end view of the parts shown in Fig. 1, the vise frame being indicated by broken lines;
- Fig. 6 is a vertical section through the right hand vise jaw, viewing the parts from the right;
- Fig. 7 is a vertical section through the toothed rod and the adjusting rod, likewise viewing the parts from the right;
- Fig. 8 is a perspective view of the adjacent ends of the adjusting rod and the adjusting sleeve prior to assembly, but with the parts in the angular relation they will assume when the sleeve is uncoupled from the adjusting rod to permit the telescoping movement;
- Fig. 9 is a view similar to Fig. 8, but with the parts in the angular relation they will assume when the sleeve is coupled to the adjusting rod;
- Fig. 10 is a perspective view of the parts shown in Fig. 8 when assembled but in the same relative angular positions;
- Fig. 11 is a view similar to Fig. 10, but with the parts in the angular relationship shown in Fig. 9;
- Fig. 12 is a fore-and-aft section on line 12—12 of Fig. 5;
- Fig. 13 is a plan view of a portion of the toothed rod in the position it will assume when disengaged from its complementary toothed section in the left hand jaw, the latter being shown in broken lines;
- Fig. 14 is a view similar to Fig. 13, but with the toothed rod shown in engaged position;
- Fig. 15 is a vertical section through the adjusting sleeve just right of the right hand jaw, the latter being broken away at the rear to illustrate a section through the toothed rod just right of the left hand jaw, the adjusting sleeve being shown coupled to the adjusting rod and the toothed rod adjusted to the position wherein it is disengaged from the complementary toothed section in the left hand jaw;
- Fig. 16 is a horizontal section through the jaws, illustrating the setting of the left hand jaw by means of the adjusting sleeve;
- Fig. 17 is a view similar to Fig. 15, but showing the adjusting sleeve uncoupled from the adjusting rod and the toothed rod engaged with the complementary toothed section in the left hand jaw;
- Fig. 18 is a view similar to Fig. 16 after the setting of the left hand jaw has been effected and with the adjusting sleeve pushed into the vise frame out of the way;
- Fig. 19 is a view similar to Fig. 18, but illustrating the parts during a centering operation, the toothed rod and the adjusting rod telescoping respectively within their associated sleeves.
- A composed line of matrices and spaces when presented at the casting level is confined endwise between a pair of vise jaws A and B mounted in the stationary portion of the so-called vise frame C (Figs. 1 and 5), and which are formed with bearing portions A¹ and B¹ slidably mounted in suitable guideways in the vise cap so that the jaws may be moved horizontally toward and from each other during a quadding or a centering operation.
- The movement of the jaws toward and from each other (see Figs. 1, 3 and 4) may be effected by quadding and centering mechanism such as that illustrated in the Frolander Patent No. 1,949,302. Suffice it to say here that the jaws A and B are operated in their movements toward and from each other through a pair of levers A² and B², the lever B² actuating the right hand jaw directly through a link B³, and the lever A² actuating the left hand jaw through a banking block C¹ connected to the lever A² through a link A³ and which actuates the left hand jaw in its different positions of adjustment, as will hereinafter be described. Either or both jaws may be connected for operation by the quadding mechanism to effect a quadding operation at the left or at the right end of the line or a centering operation as desired.
- In order that the left hand jaw A may partake of the movement of the banking block C¹, the two are connected by a toothed rod D having a reduced portion d at its left end where it is journaled in the banking block and secured against longitudinal movement with respect thereto by a cap d¹ pinned at the end of the rod and abutting against one face of the banking block and by a shoulder presented by the larger portion d² of the toothed rod, abutting against the opposite face of the block C¹. The toothed rod D extends longitudinally through the jaw A, which latter is drilled for the purpose and is recessed in its bottom portion to provide clearance for the block C¹.
- As shown in Figs. 3, 13 and 14, the toothed rod D is formed with teeth D¹ in two of its opposite faces, the other opposite faces D² being flat and, when the rod is turned to the position shown in Figs. 3 and 14, the teeth thereon will interlock with a section of complementary teeth A⁴ formed in the left hand jaw A, in which position of adjustment the left hand jaw will move as a unit with the banking block as the latter is actuated during a quadding or centering operation. When the toothed rod D is turned through an angle of 90°, the flat portions D² thereof will be brought opposite the toothed section A⁴ and, as the vise jaw immediately above and below the rod is cut away for clearance, as at D³ (Fig. 7), there will be no connection between the rod and jaw (see also Fig. 13), and the latter may be then adjusted longitudinally of the rod D to any position desired to accommodate lines of different measure.
- From the standpoint of operation, the teeth on the rod D could be formed at right angles to the axis of the rod as shown in Fig. 1. Actually however, they are given a slight pitch as shown in Figs. 13 and 14, merely as a manufacturing expedient.
- The toothed rod D spans the space between the jaws A and B and at its right end enters a sleeve B⁴ arranged coaxially therewith and which extends through the right hand jaw B (Figs. 2 and 16). The sleeve B⁴ is journaled at its right end in a bifurcated bracket F screwed to the vise frame and held against longitudinal movement with respect thereto in a manner hereinafter set forth. With this arrangement, the toothed rod, during a centering or a quadding operation involving the movement of the left hand jaw, will telescope within the sleeve B⁴. During a quadding or a centering operation involving the movement of the right hand jaw B, the latter will move with respect to the sleeve B⁴, the right hand jaw being slideable with respect to the sleeve for this purpose.
- It might be stated at this point that the toothed

rod D is adjusted to its different positions into and out of engagement with the complementary toothed section in the left hand jaw A by rotating the sleeve B⁴, and for this purpose the sleeve, 5 at its left end, is equipped (see Figs. 3 and 6) with a pair of opposed inwardly projecting portions b presenting flat surfaces that engage the flat faces D² of the toothed rod D (Fig. 6). Consequently, as the sleeve is turned, so is the rod, the portions b 10 serving the additional purpose of guiding the rod D during its telescoping movement within the sleeve. The means for rotating the sleeve to effect the adjustment of the rod will later be described.

15 The left hand jaw A is adjusted to different positions with respect to the toothed rod D by means which include an adjusting rod G projecting at its left end into the left hand jaw to which it is fixedly secured by a screw g, and at its right end into an adjusting sleeve G¹ somewhat similar to the sleeve B⁴ associated with the toothed rod D. As 20 in the case of the toothed rod and its associated sleeve, the adjusting rod G telescopes within the sleeve G¹ during a quadding left or a centering operation, and likewise, during a quadding right or a centering operation, the right hand jaw B slides with respect to said sleeve G¹. The adjusting sleeve G¹ is also similar to the sleeve B⁴ in that it is journaled in the bracket F and is adjustable 25 rotatably from a normal position wherein in the rod G is slidable longitudinally with respect thereto through 90° in a clockwise direction (looking at the machine from the right) into a position wherein the rod G is coupled to the adjusting sleeve. The sleeve G¹ differs from the sleeve B⁴ in that it is adjustable longitudinally, and when it and the adjusting rod are coupled together, an adjustment of the sleeve will effect a corresponding adjustment of the left hand jaw.

30 40 The devices for effecting the coupling and uncoupling of the sleeve G¹ and the adjusting rod G are illustrated in Figs. 8 to 11. As there shown, the sleeve G¹ is slotted longitudinally for a short distance at its left end to receive a flat key G² secured in position by a screw g¹ extending radially inwardly from the outer face of the sleeve, the key G² thus presenting a raised flat surface on the inner face of the sleeve. The adjusting rod G likewise presents a flat surface G³, but throughout its entire length, and when the parts bear the angular relation illustrated in Figs. 8 and 10, the flat surfaces will be in contact, permitting the telescoping movement between the parts as previously mentioned.

viously described, the slight movement imparted to the jaw A with respect to the rod, brought about as a result of rotating the rod a quarter turn between its locking and unlocking positions, 5 is compensated by a proper adjustment in the position of the scales G¹.

After the left hand jaw A has been adjusted to the desired position, the sleeve G¹ (while still extended) is rotated back to its normal position 10 where it is arrested by the engagement of the detent H² in the groove G⁵ (Figs. 5 and 17) and, during this operation, the sleeve G¹ is uncoupled from the adjusting rod G and the toothed rod D rotated back into engagement with the toothed 15 section A⁴ in the left hand jaw, thereby locking said jaw in its newly adjusted position.

It will be recalled that in the uncoupled condition, the adjusting sleeve G¹ is slideable with respect to the adjusting rod G, thus permitting the 20 sleeve G¹ to be returned to its normal position within the jaw B where it is out of the way, merely by pushing the sleeve inwardly (see Fig. 18). As the sleeve is pushed in, its normal angular position is maintained by the detent H² which 25 remains seated in the groove G⁵ during the sliding movement. As the detent strikes the pin G⁶ in the sleeve, it is cammed upwardly, permitting the pin to pass beneath it, but thereafter immediately reseats in the groove, thus holding the sleeve 30 both in its normal, angular and longitudinal positions, as previously described. This camming action of the pin is facilitated by forming the detent immediately adjacent the pin (see Fig. 12) with a pair of cam surfaces g⁵ and g⁶, the outer 35 surface g⁵ having less pitch than the inner surface g⁶. With this arrangement, as the pin strikes the surface g⁵ as the sleeve is pushed in, the detent will readily be cammed upwardly, whereas when the pin passes the detent, the latter, due to the greater pitch of the surface g⁶, 40 will push the sleeve home and also prevent accidental withdrawal thereof. The sleeve G¹ in its normal position, but with the jaw A set for a line of less than normal length, is illustrated in Fig. 18.

45 In order to reset the left hand jaw A to a different position, the same procedure is followed as just described, except that the adjusting sleeve G¹ must first be pulled out to the setting corresponding to the adjustment of the jaw in order 50 to aline the key G² with the recess G⁴ in the adjusting rod, so that the sleeve can be rotated to effect the coupling of the members.

During a quadding operation involving movement of the left hand jaw, the toothed rod D and 55 the adjusting rod G will telescope within their respective sleeves B⁴ and G¹; and during a quadding operation involving movement of the right hand jaw, the latter will slide with respect to said sleeves which, at the time, are both locked 60 against longitudinal movement. A centering operation which involves movement of both jaws, and which therefore gives rise to both of the conditions just stated, is illustrated in Fig. 19.

In the accompanying drawings, the invention 65 has been shown merely by way of example and in preferred form and obviously many variations and modifications may be made therein which will still be comprised within its spirit. It is to be understood, therefore, that the invention is 70 not limited to any specific form or embodiment, except in so far as such limitations are specified in the appended claims.

Having thus described my invention, what I claim is:

75 1. In a slug casting machine, the combination

of an adjustable line confining jaw, means for securing the jaw in its different adjusted positions, an adjusting rod associated with said jaw, and an operating member for said rod telescopically connected thereto.

5

2. In a slug casting machine, the combination of an adjustable line confining jaw, means for securing said jaw in its different adjusted positions, and adjusting means for the jaw including a pair of members relatively adjustable and 10 adapted in one position of adjustment to be coupled for conjoint longitudinal movement, and in another position of adjustment to be uncoupled for relative longitudinal movement.

3. In a slug casting machine, the combination 15 of an adjustable line confining jaw, a toothed rod to which the jaw is locked in its different positions of adjustment, means for adjusting the jaw when unlocked from the rod, said means including a pair of members relatively adjustable 20 and adapted in one position of adjustment to be coupled for conjoint longitudinal movement whereby said jaw may be adjusted, and in another position of adjustment to be uncoupled for relative longitudinal movement, and means for automatically effecting unlocking of the jaw and toothed rod as said members are coupled for conjoint movement and locking of the jaw and rod as the members are uncoupled for relative movement.

30

4. In a slug casting machine, the combination 35 of a pair of line confining jaws, one adjustable to accommodate lines of different measure, means for securing the jaw in its different positions of adjustment, and an adjusting device associated with the adjustable jaw and extending along the opposite jaw to within convenient reach of the operator, said device including a pair of members relatively adjustable and adapted in one position 40 of adjustment to be coupled for conjoint longitudinal movement whereby said jaw may be adjusted, and in another position of adjustment to be uncoupled for relative longitudinal movement so as to be positionable out of the way 45 when the jaw is adjusted for lines of less than full measure.

40

5. In a slug casting machine, the combination 50 of a pair of line confining jaws, one adjustable to accommodate lines of different measure, means for securing the jaw in its different positions of adjustment, and an adjusting device including an adjusting rod fixed to the adjustable jaw, a sleeve extended along the opposed jaw and into which said rod projects, and connections between the rod and sleeve whereby the sleeve may be 55 coupled with the adjusting rod to effect movement of the latter longitudinally in adjusting the jaw, said connections being such that after adjustment of the jaw has been effected said sleeve and rod may be uncoupled and the sleeve 60 pushed back out of the way.

50

6. In a slug casting machine, the combination 65 of a pair of line confining jaws movable one toward the other in quadding, and means for adjusting one of said jaws to vary the normal degree of separation thereof to accommodate lines of different measure, said means including an adjusting rod secured to one of said jaws and arranged to telescope into the other jaw during 70 a quadding operation.

60

7. In a slug casting machine, the combination 75 of a pair of line confining jaws movable one toward the other in quadding, means including a toothed rod for locking one of said jaws in different positions of adjustment to accommodate

70

75

lines of different measure and movable with said jaw during a quadding operation, means for effecting locking and unlocking of said jaw and toothed rod, means for adjusting the jaw to 5 different positions with respect to the rod while unlocked therefrom, and means whereby said toothed rod may telescope into the other jaw during a quadding operation.

8. In a slug casting machine, the combination 10 of a pair of line confining jaws movable one toward the other in quadding, a movable block associated with one of said jaws through which the quadding movement thereof is effected, a toothed rod journalled in said block and secured 15 against longitudinal movement with respect thereto, said rod being engageable with said jaw in the different adjusted positions of the latter, and means for effecting the engagement and disengagement of the toothed rod and jaw 20 and for adjusting the jaw when disengaged to different positions to accommodate lines of different measure, said means including an adjusting rod secured to the first mentioned jaw and a sleeve extending along the other jaw and into which the 25 adjusting rod projects, said sleeve being adjustable to one position to be coupled with the adjusting rod to effect adjustment of the jaw and to another position to be uncoupled from the rod whereby the latter may telescope within the 30 sleeve during quadding operations and the sleeve pushed back out of the way after adjustment of the jaw has been effected.

9. In a slug casting machine, the combination 35 of a pair of line confining jaws movable one toward the other in quadding, a movable block associated with one of said jaws through which the quadding movement thereof is effected, a toothed rod movable with said block and adapted to be locked to said jaw in different adjusted 40 positions of the latter, an adjusting rod secured to said jaw and projecting into a sleeve extending along the second jaw, said sleeve in one position of adjustment providing for relative longitudinal movement between it and the adjusting rod and in another position of adjustment being coupled to said rod for conjoint longitudinal movement whereby the first mentioned jaw may be adjusted to different positions to accommodate lines of different measure, and means for unlocking 45 the toothed rod and jaw as the adjusting sleeve is coupled with the adjusting rod, and for locking the toothed rod and jaw together as the adjusting sleeve is uncoupled from said adjusting rod.

10. In a slug casting machine, the combination 50 of a pair of line confining jaws movable one toward the other in quadding, a movable block associated with one of said jaws through which the quadding movement thereof is effected, a toothed section on said jaw, an adjustable toothed rod 55 movable with said block and adapted in one position of adjustment to engage the toothed section to lock the jaw and rod against relative longitudinal movement, and in another position of adjustment to be disengaged from the toothed section to permit relative longitudinal movement between the jaw and toothed rod, an adjusting rod secured to said jaw and extending into the 60 second jaw, and means within convenient reach 65 of the operator for effecting the engagement and disengagement of the toothed rod with and from the toothed section, and for effecting the adjustment of the first mentioned jaw through the adjusting rod when the toothed rod is in its disengaged position, said toothed rod and said adjust- 70

ing rod during a quadding operation telescoping within the second mentioned jaw.

11. In a slug casting machine, the combination 5 of a pair of line confining jaws movable one toward the other in quadding, a movable block associated with one of said jaws through which the quadding movement thereof is effected, a toothed section on said jaw, an adjustable toothed rod movable with said block and extending into the opposite jaw, said rod being adapted in one position of adjustment to engage the toothed section on said first jaw and in another position of adjustment to be disengaged from said jaw to permit adjustment of the latter, an adjusting rod fastened to the first jaw and projecting into a 15 sleeve extending along the second jaw, said sleeve in one position of adjustment being coupled to the adjusting rod whereby the latter may be moved to effect adjustment of the first jaw to different positions to accommodate lines of different measure, and in another position of adjustment being uncoupled from the adjusting rod whereby said sleeve may be pushed back out of the way, and means operating automatically as the sleeve is coupled with the adjusting rod to 20 effect disengagement of the toothed rod from the toothed section, and as the sleeve is uncoupled from said rod to effect re-engagement of the toothed rod with the toothed section.

12. In a slug casting machine, the combination 30 of a pair of line confining jaws movable one toward the other in quadding, a movable block for the left hand jaw through which the quadding movement of the jaw is effected, a toothed section on said jaw, an adjustable toothed rod movable 35 with said block and adapted in one position of adjustment to engage the toothed section to lock the jaw against relative longitudinal movement with respect thereto, and in another position of adjustment to be disengaged from the jaw to 40 permit relative longitudinal movement, a sleeve extending along the right hand jaw and into which the toothed rod telescopes, said sleeve being adapted upon rotation to effect the adjustment of the toothed rod into and out of locking engagement with the left hand jaw, a second sleeve also extending along the right hand jaw, an adjusting rod secured to the left hand jaw and telescoping 45 into the second sleeve, said sleeve in one position of adjustment being slidable longitudinally 50 with respect to the adjusting rod and in another position of adjustment being coupled to said rod whereby the left hand jaw may be adjusted to different positions to accommodate lines of different measure, means for automatically adjusting 55 the first sleeve to effect disengagement of the toothed rod from the left hand jaw as the second sleeve is coupled with the adjusting rod and for automatically effecting reengagement of the toothed rod and jaw as the second sleeve is uncoupled from the adjusting rod.

13. In a slug casting machine, the combination 60 of a pair of line confining jaws movable one toward the other in quadding, a movable block for the left hand jaw through which the quadding movement 65 of the jaw is effected, a toothed section on said jaw, an adjustable toothed rod movable with said block and adapted in one position of adjustment to engage the toothed section to lock the jaw against relative longitudinal movement with respect thereto, and in another position of adjustment to be disengaged from the jaw to 70 permit relative longitudinal movement, a sleeve extending along the right hand jaw and into which the toothed rod telescopes, said sleeve be- 75

ing adapted upon rotation to effect the adjustment of the toothed rod into and out of locking engagement with the left hand jaw, a second sleeve also extended along the right hand jaw, and an adjusting rod secured to the left hand jaw and telescoping into said second sleeve, said sleeve in one position of adjustment being uncoupled from the adjusting rod and in another position of adjustment being coupled to said rod whereby the latter may be moved to effect the adjustment of the left hand jaw to different positions to accommodate lines of different measure.

14. In a slug casting machine, the combination of a pair of line confining jaws movable one toward the other in quadding, a movable block for the left hand jaw through which the quadding movement of the jaw is effected, a toothed section on said jaw, an adjustable toothed rod movable with said block and adapted in one position of adjustment to engage the toothed section to lock the jaw against relative longitudinal movement with respect thereto, and in another position of adjustment to be disengaged from the jaw to permit relative longitudinal movement, a sleeve extending along the right hand jaw and into which the toothed rod telescopes, said sleeve being adapted upon rotation to effect the adjustment of the toothed rod into and out of locking engagement with the left hand jaw, a second sleeve also extended along the right hand jaw, an adjusting rod secured to the left hand jaw and telescoping into said second sleeve, said sleeve in one position of adjustment being uncoupled from the adjusting rod and in another position of adjustment being coupled to said rod whereby the latter may be moved to effect the adjustment of the left hand jaw to different positions to accommodate lines of different measure, and means for automatically adjusting the first sleeve to effect disengagement of the toothed rod from the left hand jaw as the second sleeve is coupled to the adjusting rod and for automatically effecting re-engagement of the toothed rod and jaw as the second sleeve is uncoupled from the adjusting rod.

15. In a slug casting machine, the combination of a pair of line confining jaws movable one toward the other in quadding, a movable block for the left hand jaw through which the quadding movement of the jaw is effected, a toothed section on said jaw, an adjustable toothed rod movable with said block and adapted in one position of adjustment to engage the toothed section to lock the jaw against relative longitudinal movement with respect thereto, and in another position of adjustment to be disengaged from the jaw to permit relative longitudinal movement, a sleeve extending along the right hand jaw and into which the toothed rod telescopes, said sleeve being adapted upon rotation to effect the adjustment of the toothed rod into and out of locking engagement with the left hand jaw, a second sleeve also extended along the right hand jaw, an adjusting rod secured to the left hand jaw and telescoping into said second sleeve, said sleeve in one position of adjustment being uncoupled from the adjusting rod and in another position of adjustment being coupled to said rod whereby the latter may be moved to effect the adjustment of the left hand jaw to different positions to accommodate lines of different measure, means for automatically adjusting the first sleeve to effect disengagement of the toothed rod from the left hand jaw as the second sleeve is coupled to the adjusting rod and for automatically effecting re-

engagement of the toothed rod and jaw as the second sleeve is uncoupled from the adjusting rod, and means for holding said second sleeve in its normal condition uncoupled from the adjusting rod.

16. In a slug casting machine, the combination of a pair of line confining jaws movable one toward the other in quadding, a movable block for the left hand jaw through which the quadding movement of the jaw is effected, a toothed section on said jaw, an adjustable toothed rod movable with said block and adapted in one position of adjustment to engage the toothed section to lock the jaw against relative longitudinal movement with respect thereto, and in another position of adjustment being disengaged from the jaw to permit relative longitudinal movement, a sleeve extending along the right hand jaw and into which the toothed rod telescopes, said sleeve being adapted upon rotation to effect the adjustment of the toothed rod into and out of locking engagement with the left hand jaw, a second rotatably adjustable sleeve also extended along the right hand jaw, an adjusting rod secured to the left hand jaw and telescoping into said second sleeve, said sleeve in one position of rotary adjustment being slidably longitudinally with respect to the adjusting rod and in another position of rotary adjustment being coupled to said rod whereby the latter may be moved to effect the adjustment of the left hand jaw to accommodate lines of different measure, a set of gears connecting the two sleeves whereby upon coupling the second sleeve with the adjusting rod the first sleeve is moved to disengage the toothed rod from the left hand jaw, and upon uncoupling the second sleeve from the adjusting rod the first sleeve is turned to effect the engagement of the toothed rod with the left hand jaw to lock the latter in its adjusted position, the telescoping arrangement of the two rods with their respective sleeves providing for the quadding movement of the jaws and that of the adjusting rod and second sleeve also permitting the latter to be pushed inwardly out of the way after adjustment of the jaw has been effected.

17. In a slug casting machine, the combination of a pair of line confining jaws movable one toward the other in quadding, a toothed rod for locking one of said jaws in different positions of adjustment to accommodate lines of different measure and movable with said jaw during a quadding operation, and devices including a sleeve extended through the opposed jaw for effecting locking and unlocking of said jaw and rod and into which said toothed rod is adapted to telescope during a quadding operation with the first mentioned jaw, said second mentioned jaw being slidable with respect to said sleeve during a quadding operation with said latter jaw.

18. In a slug casting machine, the combination of a pair of line confining jaws movable one toward the other in quadding, means for adjusting one of said jaws to different positions to accommodate lines of different measure, said means including an adjusting rod secured to said jaw and a sleeve extended through the opposed jaw into which said rod is adapted to telescope during a quadding operation with said first jaw, and means for coupling said sleeve with the adjusting rod for conjoint movement to permit the adjustment of the first mentioned jaw, said second mentioned jaw being slidable with respect to said sleeve during a quadding operation with the latter jaw.

19. In a slug casting machine, the combination of a pair of line confining jaws movable one toward the other in quadding, and means for locking one of said jaws in different positions of adjustment to accommodate lines of different measure, said means including a toothed rod rotatably mounted for engagement with and disengagement from the adjustable jaw but movable with the jaw during quadding, and a relatively stationary sleeve into which the toothed rod telescopes during a quadding movement of the adjustable jaw, said sleeve being rotatably mounted and coupled to the toothed rod so as to rotate the latter in effecting its engagement with and disengagement from the adjustable jaw.
20. In a slug casting machine, the combination of a pair of line confining jaws movable one to-
- ward the other in quadding, and means for adjusting one of the jaws to different positions to accommodate lines of different measure, said means including a rod fixed to the adjustable jaw and movable therewith both during quadding and adjustment, a rotatably mounted sleeve into which the rod projects at the end remote from the jaw, and coupling means between the sleeve and rod, said coupling means in one rotary position of the sleeve permitting the rod to telescope freely within the sleeve during quadding or the sleeve to telescope with the rod after a jaw adjustment, and in another rotary position of the sleeve providing for the longitudinal movement of the rod and sleeve as one in effecting the adjustment of the jaw.

JOHN H. HILPMAN.
